Primary Examiner — Catherine Tuttle(74) *Attorney, Agent, or Firm* — Daniel N. Smith(57) **CLAIM**

The ornamental design for a puck visor hockey training tool, as shown and described.

DESCRIPTION

FIG. 1 is a front view of a puck visor hockey training tool, showing my new design;

FIG. 2 is a rear view of the puck visor hockey training tool;

FIG. 3 is a top view of the puck visor hockey training tool;

FIG. 4 is a bottom view of the puck visor hockey training tool;

FIG. 5 is a left-side view of the puck visor hockey training tool;

FIG. 6 is a right-side view of the puck visor hockey training tool;

FIG. 7 is a front view of the puck visor hockey training tool, shown in use on a hockey jersey; and,

FIG. 8 is a top isometric view of the puck visor hockey training tool, shown in use on a hockey jersey.

The broken lines showing the human figure with jersey in FIGS. 7 and 8 form no part of the claimed design, but are included for the purpose of illustrating the puck visor hockey training tool in its environment.
